UNITED STATES PATENT OFFICE.

JOHN BYERS, OF BROOKLYN, ASSIGNOR TO CORLISS BROS. & CO., OF TROY,
NEW YORK.

DESIGN FOR A COLLAR.

SPECIFICATION forming part of Design No. 18,518, dated August 14, 1888.

Application filed June 25, 1888. Serial No. 278,152. Term of patent 14 years.

To all whom it may concern:

Be it known that I, JOHN BYERS, a citizen of the United States, residing in the city of Brooklyn, in the county of Kings and State of New York, have invented and produced a new and original Design for Apparel-Collars, of which the following is a specification, reference being had to the accompanying drawing, which represents my new design.

My design for apparel-collars is distinguished from all others by having the forward end portions of the collar formed with standing upper front edges, A, edges B, inclined forward and downward from the lower ends of the standing edges A, and tapering tabs C, inclined downward and outward from along the inclined edges B.

What I claim is—

The design for an apparel-collar comprising the standing upper front edges, A, the edges B, inclined downward and forward from the lower ends of said standing edges, and tapering tabs C, inclined downward and outward from along said inclined edges, substantially as shown and described. 25

In testimony whereof I hereunto set my hand, in the presence of two subscribing witnesses, this 20th day of June, 1888.

JOHN BYERS.

Witnesses:

THOS. S. BRESLIN,
JAMES A. PATERSON.
